UNITED STATES PATENT OFFICE.

HOWARD S. CRAVER, OF CHICAGO, ILLINOIS, ASSIGNOR OF ONE-HALF TO HENRY S. JUDD, OF CHICAGO, ILLINOIS.

WASHING-MACHINE.

1,361,228.

Specification of Letters Patent. Patented Dec. 7, 1920.

Application filed December 26, 1919. Serial No. 347,558.

To all whom it may concern:

Be it known that I, HOWARD S. CRAVER, a citizen of the United States, residing at Chicago, in the county of Cook and State 5 of Illinois, have invented a certain new and useful Improvement in Washing-Machines, of which the following is a specification.

My invention relates to washing machines especially of the type wherein plungers, frequently called "vacuum cups", reciprocate vertically and at the same time have an intermittent rotary motion. In washing machines operating upon this principle the clothes sometimes become wrapped around 10 the center post, thus choking the machine and damaging the clothes. The general object of my invention is to provide means whereby the plungers will, in addition to their vertical movement, be caused to rotate intermittently, first in one direction and then in the other direction, thus preventing the clothes from being wound around the center post.

I accomplish my objects by the mechanism 25 illustrated in the accompanying drawings, in which—

Figure 1 is an assembly view of practically the complete machine showing the tub or receptacle in central vertical section.

Fig. 2 is a plan view of the ratchet wheel, pawl and associated parts.

Fig. 3 is a central vertical section of the parts shown in Fig. 2.

Fig. 4 is a view looking toward the left 35 in Fig. 3 but showing the entire ratchet wheel and pawl carrier instead of only a portion thereof as in Fig. 3.

Fig. 5 is a perspective view of the ratchet wheel.

Fig. 6 is similar to Fig. 2, but shows the 40 large tooth of the double pawl in engagement with the ratchet wheel.

Fig. 7 is a perspective view of the double pawl.

Fig. 8 is similar to Fig. 2, but shows the 45 parts in changed position.

Fig. 9 is a front elevation of the parts shown in Fig. 8.

Fig. 10 is a bottom plan view of the parts 50 shown in Fig. 9.

Like numerals denote like parts throughout the several views.

In the form selected to illustrate the in-

vention, a clothes receptacle 1 is mounted upon a stationary frame 2 of any suitable 55 design. At the center of the receptacle is a center post 3 which is hollow and forms a guide for the main shaft 4. A yoke 5 is fastened to the shaft above post 3 and carries two vertical stems 6 which extend into 60 the sleeves 7 of the plungers or vacuum cups 8. The parts thus far described are standard and may assume various shapes and sizes.

Power may be derived from various 65 sources, but in the illustrated form is furnished by an electric motor 12 supported in a frame 13 pivoted upon a stationary pin 14. The frame is also suspended in part from a stationary screw 16 which is provided with a nut 17 upon which one side of the frame rests. These parts constitute an adjustable suspension for the motor. The power from the motor is delivered through a belt 20 to a sheave 22 rigidly fastened to 70 a shaft 23 provided with a pinion 24 which meshes with a gear wheel 25, rigidly fastened to a shaft 26. An arm 28 is rigidly fastened to shaft 26, the same constituting a crank which is connected by means of a 75 link or pitman 30 to the main operating lever 32. Lever 32 is pivoted at one end of a stationary pin 33 and at the other end is connected by a link 34 to a coupling 36 which is so constructed that it controls the 80 position of shaft 4 vertically, but permits it to rotate although the coupling itself is non-rotatable. It is evident that when the motor causes the wheels to rotate, the link 30 and lever 32 will move up and down and 85 produce a corresponding vertical movement of the main shaft 4 and vacuum cups 8.

Rigidly fastened to shaft 4 above the coupling 36 is a ratchet wheel 40. Its teeth are of special design and will be presently 90 described. The ratchet wheel co-operates with a double pawl which is provided with two teeth 42 and 43. The pawl is mounted in a carrier 45 and while the design may be varied, said carrier has a cylindrical 95 chamber 46 formed in it which extends radially with respect to the ratchet wheel. It forms a guide for the cylindrical portion 48 of the pawl. A stem 49 extends backward from this cylindrical portion and out 100 through a suitable aperture in the outer end 105

of the carrier. Rotation of the pawl about its longitudinal axis is prevented by a pin 50 which extends transversely through stem 49 and works in a slot 52 formed in the 5 outer end of the carrier. A helical compression spring 53 is interposed between the back of the cylindrical portion 48 and the end of chamber 46, thus constantly urging the pawl toward the ratchet wheel.

- 10 The teeth or pawls 42, 43 face in opposite directions and the upper one is longer than the lower one. The purpose of this is to enable the upper and longer one to ride upon the top, blank surface of the ratchet wheel 15 and thus form a support for the pawl and pawl carrier and hold the shorter tooth in the plane of the ratchet wheel when the latter is being driven in one direction. The upper tooth is so long that when the lower 20 tooth is in engagement with the ratchet wheel the upper tooth will project radially inward beyond the root of the ratchet teeth, thus preventing the longer tooth from dropping down into the spaces between the teeth. 25 The pawl carrier makes a loose fit upon shaft 4 and in practice is lubricated so that it will slide freely in a vertical direction upon the shaft and will also freely oscillate about the shaft as an axis.
- 30 While the shape of the teeth may be altered somewhat without departing from the spirit of the invention, a good form is shown in the drawings in which the ratchet teeth 35 56 are in the form of pins, the acting faces whereof extend radially or at least near enough so to justify the statement that the teeth face in both directions, one side of a tooth being adapted to coöperate with one of the pawl teeth and the other with the other. While not essential, it is desirable 40 that the spaces between the teeth contain obtuse angled points 57, the function whereof is chiefly to constitute fillets for reducing the clicking noise which might otherwise be 45 produced, as the pawl teeth slide over them. These fillets also improve the action of the ratchet.

As the ratchet wheel is rigidly fastened to the shaft, it, of course, moves vertically with 50 it and when the ratchet is rotated it will impart a corresponding rotary movement to the main shaft. The pawl carrier 45 is supported directly or indirectly by the ratchet wheel and receives an oscillatory movement 55 about shaft 4 as an axis by means of a stud 60 which screws into a threaded aperture 61 arranged radially at the outer end of the pawl carrier, as best shown in Fig. 3. Any other suitable means, however, may be substituted for fastening the stud to the carrier. Said stud extends through a slot 62 formed at the end of an arm 64 fastened to 60 and forming a part of the lever 32 shown in Fig. 1. The construction is such that as 65 the arm 64 swings in an arc centered at pin

33, it will oscillate the pawl carrier about shaft 4 as an axis and cause the pawl teeth to drive the ratchet wheel in one direction or the other depending upon which of the two pawl teeth are in engagement with the ratchet wheel at the time.

It will be evident that as the pawl carrier is freely slideable upon shaft 4 its weight will always urge it to descend as far as possible. When in lowered position the long 75 tooth 42 will engage the ratchet teeth 56 as shown in Fig. 10 and will drive the ratchet wheel in an anticlockwise direction when viewed from the bottom as in Fig. 10, or in a clockwise direction when viewed from the 80 top; but a cam 66 is formed upon the top of the ratchet wheel and this is so shaped that when the wheel has been rotated by the longer pawl tooth a certain amount, the cam will slip under the pawl carrier and force it 85 upward to the position shown in Figs. 3 and 4. This causes the long tooth to be shifted up out of the plane of the ratchet wheel, whereupon spring 53 forces it radially inward so far that the point of the tooth extends to a point inside of the root circle of the ratchet wheel and thus prevents the long tooth from descending again even after the cam has been rotated out from under the 90 pawl carrier. This upward shifting of the long tooth brings the short tooth up into the plane of the ratchet wheel, with the result that the oscillatory movement of the pawl carrier causes the ratchet wheel to be driven in the reverse direction. This reverse rotation of the ratchet wheel under the action of the short tooth 43 continues until the long tooth, which is now riding upon the upper surface of the ratchet wheel, comes to the large notch 68 formed in the periphery 100 of the ratchet wheel. This is larger than the long tooth, and hence permits it to drop down into it, as illustrated in Fig. 6. The result is that the long tooth is once more in the plane of the ratchet wheel. The sides of 105 notch 68 are so formed as to produce a ratchet tooth faced in such direction as to be actuated by the long tooth of the pawl, consequently the oscillatory movement of the pawl carrier now causes the long tooth to 110 drive the ratchet wheel in the reverse direction. This completes the cycle of operation, the long tooth driving the ratchet wheel when the pawl carrier is lowered and the short tooth driving it when the pawl carrier is raised. In order to render the device 115 smooth acting and assure the descent of the long tooth when it arrives at the notch 68, it is desirable to bevel the upper surface of the ratchet wheel at the point 70 adjacent 120 to the entering side of the notch. This permits the long tooth and supported parts to descend gradually and certainly. This construction also avoids the production of noise 125 incident upon the descent of the parts. 130

The long pawl tooth 42 is so long that when it is seated in engagement with the ratchet teeth, the point of the short tooth will be outside of the point circle of the ratchet teeth—that is, will be prevented from reaching the ratchet teeth, and hence will be maintained nonactive while the long tooth is acting, this characteristic being clearly illustrated in Fig. 10.

10 Although a matter chiefly of design, it is desirable that the pawl carrier be provided with a counterweight 72 located on the opposite side of the shaft from the pawl, thus tending to balance the carrier and promote 15 the ease and certainty with which it will slide along the main shaft.

The operation of the device will now be readily understood. The oscillatory movement of the main lever 32 causes the vacuum 20 cups 8 to rise and fall and at the same time causes the pawl carrier to oscillate about shaft 4. Assuming that the carrier is in down position with the long tooth 42 in engagement with the ratchet wheel; the ratchet 25 wheel and shaft will be rotated intermittently in a direction in which the long tooth faces. Finally, however, the lifting cam 66 comes into action, raises the pawl carrier to the position shown in Figs. 2 and 3, 30 brings the short tooth into the plane of the ratchet wheel, and causes the spring 53 to project the long tooth over the blank surface of the ratchet wheel. The short tooth now commences to act and intermittently rotates 35 the ratchet wheel in the opposite direction. The vertical reciprocation of the vacuum cups is, of course, maintained during the entire time, but whereas the long tooth intermittently rotates them in one direction, 40 the short tooth intermittently rotates them in the opposite direction. The action of the short tooth is continued until the notch 68 is reached, whereupon the pawl carrier drops down to the lower position and the 45 long tooth comes into action once more.

I do not herein claim the ratchet broadly but have done so in a divisional application filed February 13, 1920, Serial No. 358,435.

Having thus described my invention what 50 I claim as new and desire to secure by Letters Patent, is:—

1. A washing machine having a clothes receptacle, a main shaft coming up through the bottom of the receptacle and provided 55 with plungers, means for reciprocating said shaft vertically, a ratchet wheel fastened to the shaft, a double pawl having teeth facing in opposite directions, means for moving said pawl back and forth for actuating said ratchet wheel, said pawl having teeth facing in opposite directions, and means for causing first one tooth and then the other tooth of the pawl to engage said ratchet wheel.

60 2. A washing machine having a clothes

receptacle, a main shaft coming up through the bottom of the receptacle and provided with plungers within the receptacle for washing clothes, an oscillating lever having a fixed pivot at one end and at the other 70 end being coupled to said shaft whereby the oscillation of the lever causes the shaft to reciprocate vertically but permits the shaft to rotate independently of the lever, and a reversing ratchet having a ratchet wheel 75 fastened to the shaft, a double pawl having teeth facing in opposite directions, means for oscillating said pawl about the shaft as an axis, and means for causing first one tooth and then the other tooth of the 80 pawl to engage said ratchet wheel.

3. A washing machine having a clothes receptacle, a main shaft coming up through the bottom of it and provided with plungers, means for reciprocating said shaft vertically, 85 a ratchet wheel fastened to the shaft and lying in a horizontal plane with teeth formed in the periphery of the wheel, a pawl having a long tooth and a short tooth, one facing in one direction and the other 90 in the opposite direction, means for moving said pawl back and forth for actuating said ratchet wheel, and means for shifting the pawl transversely to the plane of the ratchet wheel for bringing first the long tooth into 95 engagement with the ratchet wheel and then the short one, the long tooth being long enough to hold the short tooth nonactive when the long tooth is in engagement with the ratchet wheel teeth and to overlie the 100 blank portion of the ratchet wheel when the short tooth is in the plane of and in engagement with the teeth of the ratchet wheel.

4. A washing machine having a clothes receptacle, a main shaft which is both rotatable and axially movable, clothes engaging elements connected to said shaft, means for reciprocating said shaft axially, a ratchet wheel connected to the shaft, a double 105 pawl having teeth facing in opposite directions, means for moving said pawl back and forth for actuating said ratchet wheel, said pawl having teeth facing in opposite directions, and means for causing first one tooth and then the other tooth of the pawl to engage 110 said ratchet wheel.

5. In a device of the class described, in combination, a support, a reciprocatory shaft in said support, and means to rotate said shaft during the reciprocation including a ratchet wheel having all of its teeth in a common plane at right angles to its axis, some of the acting faces of the ratchet teeth facing in one direction and others facing in the opposite direction, 125 a double pawl for actuating said ratchet wheel, said pawl having one tooth facing in one direction and another tooth facing in the opposite direction, the ratchet wheel and pawl being capable of relative 130

motion in the direction of the axis of the wheel, and means for periodically causing relative motion between the wheel and pawl in the direction of the wheel axis for reversing the direction of rotation of the shaft.

6. In a washing machine, a clothes receptacle, a reciprocatory and rotary shaft supported vertically in said receptacle, a ratchet wheel connected to said shaft, said wheel having teeth all arranged in a common plane and with acting faces some of which face in one direction and others face in the opposite direction, a double tooth pawl, means for oscillating said pawl for rotating the ratchet wheel and shaft, means for periodically shifting the pawl axially for reversing the direction of the ratchet wheel after a plurality of angular movements thereof, and means for producing a reciprocatory

movement of the shaft for every angular movement of the ratchet wheel.

7. In a washing machine of the class wherein plungers are spaced at a distance from each other and carried by arms which have a step by step angular or rotary movement and also a reciprocatory movement in a direction at right angles to the plane of rotation, and the arms are carried at the upper end of a shaft which projects up through the bottom of the clothes receptacle and is actuated by mechanism beneath said receptacle, means for periodically reversing the direction of rotation of the arms after they have taken a plurality of angular steps in a given direction.

In witness whereof I have hereunto subscribed my name.

HOWARD S. CRAVER.
